P. SPIEGEL

COMBINED BRUSH AND TUMBLER BRACKET

Filed Aug. 18, 1922

Inventor.

Paul Spiegel,
By his Attorney, Geo. W. Knapp

Patented Aug. 26, 1924.

Des. 65,503

UNITED STATES PATENT OFFICE.

PAUL SPIEGEL, OF NEW YORK, N. Y.

DESIGN FOR A COMBINED BRUSH AND TUMBLER BRACKET.

Application filed August 18, 1922. Serial No. 3,439. Term of patent 7 years.

To all whom it may concern:

Be it known that I, PAUL SPIEGEL, a citizen of the United States, and a resident of the borough of Bronx, county of Bronx, city and State of New York, have invented a new, original, and ornamental Design for a Combined Brush and Tumbler Bracket, of which the following is a specification, reference being had to the accompanying drawing, forming part thereof.

The figure is a perspective view of a combined brush and tumbler bracket showing my new design.

I claim:

The ornamental design for a combined brush and tumbler bracket, as shown.

PAUL SPIEGEL.

Witnesses:

ALBERT KIMBRIG,
JULIA WILLNER.
